UNITED STATES PATENT OFFICE.

CHARLES T. MITCHELL, OF WASHINGTON, DISTRICT OF COLUMBIA, AS-
SIGNOR OF ONE-HALF TO WILLIAM E. ARRINGTON, OF WASHINGTON,
DISTRICT OF COLUMBIA.

COMBINED WINDOW-SHADE AND CURTAIN-POLE BRACKET.

SPECIFICATION forming part of Letters Patent No. 721,062, dated February 17, 1903.

Application filed August 7, 1902. Serial No. 118,815. (No model.)

To all whom it may concern:

Be it known that I, CHARLES T. MITCHELL, a citizen of the United States, residing at Washington, in the District of Columbia, have 5 invented certain new and useful Improvements in a Combined Window-Shade and Curtain, &c., Pole Bracket; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 My invention relates to a new and improved bracket for the twofold purpose of supporting or retaining in position in a window-casing the ordinary shade and a lace-curtain or lambrequin pole. It is chiefly characteristic for great simplicity and consequent 20 cheapness of manufacture for carrying out the above-named purposes. It can be applied with the least expenditure of time and trouble and without any special adaptation 25 for its application or adoption.

In the accompanying drawings, Figure 1 illustrates the invention as applied for use. Fig. 2 is a transverse vertical section showing one of the brackets, and Fig. 3 is a detached perspective view.

30 In the embodiment of my invention I construct a bracket 1, two such being required to utilize the same for the purposes herein named. Said bracket, preferably a casting 35 of brass, comprises a substantially straight member 1^a, having integral with its upper edge near the inner end an upward extension 1^b, produced with a gain or slot 1^{bb}, the companion bracket, however, having an orifice 40 or recess, as well understood, to provide for the reception of the usual gudgeon applied to the ends of the ordinary window-shade roll for supporting the last-named in place by means of said brackets. Extending laterally 45 from and integral with said extension 1^b is a short, preferably cylindric, stud 1^c, in turn formed integrally with a plate 1^d, arranged parallel with the member 1 and having suitably-disposed openings or apertures 1^x there- 50 through for receiving fastenings, as screws,

&c., for securing the brackets to the window-casing upon its opposite-facing surfaces. This construction, it will be observed, permits the arrangement or disposition of the window-shade roll within the plane of the 55 window-casing, which is the preferable way of doing the same and as is ordinarily practiced in this respect in the suspending or hanging of window-shades with the use of the common form of bracket. Said straight 60 member 1^a has also projecting therefrom upon its upper edge at the outer end an upstanding horizontal arm or member 2, also integral or in one with said straight member 1^a. Said member or arm 2 is constructed or 65 adapted to form, at its upper or free end preferably, an upwardly-opening loop or eye 2^a, constituting, with a companion bracket the counterpart of the above described, a support for the pole of a lace curtain or lambrequin, as will be readily appreciated. This construction provides for supporting the pole within limits corresponding to the width of the window-casing opening and yet beyond the window-casing out of alignment with the 70 shade-roll. It is also obvious that my invention can be made and applied at the minimum 75 or least expense.

Having thus described my invention, what I claim as new, and desire to secure by Letters 80 Patent, is—

1. A window-shade bracket, embracing an arm member having, near one end, a lateral fastening-plate and an upstanding trunnion-receiving extension arranged parallel with 85 said fastening-plate and in the plane of said arm member, and a pole-receiving upstanding loop at the opposite end of said arm member.

2. A window-shade bracket, embracing an 90 arm member having, near one end, a lateral fastening-plate offset or distant therefrom, also having, near said end, a trunnion-receiving upstanding extension arranged parallel with said fastening-plate and in the 95 plane of said arm member, and a pole-receiving upstanding loop arranged at the opposite end of said arm member.

3. A window-shade bracket, embracing an arm member having, near one end, a lateral 100

stud provided with a fastening-plate, and also having near said end, an upstanding trunnion-receiving extension arranged in the plane of said arm member, and an upstanding pole-receiving loop arranged at the opposite end of said arm member and also in the plane of said member.

In testimony whereof I affix my signature in presence of two witnesses.

CHAS. T. MITCHELL.
